UNITED STATES PATENT OFFICE.

CHARLES W. STARKER, OF PITTSBURGH, PENNSYLVANIA, ASSIGNOR TO WESTINGHOUSE ELECTRIC AND MANUFACTURING COMPANY, A CORPORATION OF PENNSYLVANIA.

COMMUTATOR CYLINDER.

Application filed January 14, 1918. Serial No. 211,774.

To all whom it may concern:

Be it known that I, CHARLES W. STARKER, a citizen of the German Empire, and a resident of Pittsburgh, in the county of 5 Allegheny and State of Pennsylvania, have invented a new and useful Improvement in Commutator Cylinders, of which the following is a specification.

My invention relates to dynamo-electric 10 machines and has special relation to commutator cylinders therefor.

The object of my invention is to provide a commutator cylinder by means of which points of equal potential throughout the 15 armature shall be connected together and by which the leads connecting these points shall be firmly supported in easily accessible positions.

Heretofore, it has been customary to connect points of equal potential in an armature by means of cross connectors situated either at the end of the commutator adjacent the armature or at the end of the armature opposite the commutator cylinder for the 25 purpose of equalizing the current flow in different portions of the armature winding, thus compensating for the current-unbalancing effect of eccentric armature mounting and differences in the permeability of 30 different pole pieces and of different portions of the frame. When the cross connections are situated at the end of the commutator cylinder adjacent the armature, they are inaccessible for inspection and repair 35 and when they are situated at the end of the armature opposite the commutator cylinder, they are inaccessible for inspection or repair and have the additional disadvantage that different potentials may be developed in the leads which connect the cross- 40 connectors to the commutator bars, resulting in different values of current flowing in parts of the armature in which the current values should be the same, the elimination 45 of which is the prime object of the cross-connections.

By my invention, I have provided a means whereby the cross-connectors are supported at the end of the commutator cylinder opposite the armature, rendering them readily accessible, and are connected directly to the commutator bars, thereby eliminating any

possibility of a difference of potential at the bars thus connected.

In the accompanying drawing, Fig. 1 is 55 a side elevational view of a portion of a dynamo-electric machine constructed in accordance with my invention, parts being broken away to illustrate the cross connections; and Fig. 2 is a sectional view of the 60 machine portion shown in Fig. 1, the section being taken along the line II-II thereof.

Referring more particularly to the drawings, I have shown a plurality of conducting bars 1 and insulating bars or strips 2 alternately disposed to form a commutator cylinder that is supported by, but insulated from, a sleeve 3 situated on the inside thereof. Bars 4 equally spaced about the periphery of the commutator cylinder project from the end thereof forming the end portions 5 to which cross-connectors 6 are attached. The end portions 5 are held rigidly in position by means of spacing blocks 7 75 formed of wood or some other suitable insulating material. The supporting sleeve 3 extends beyond the main body of the commutator cylinder and provides a supporting means for the end portions 5 of the commutator bars 4, the cross-connectors 6 and the spacing blocks 7 which are held thereagainst by means of banding wire 8 which is also insulated therefrom.

While I have described a commutator having equi-spaced bars projecting from the end of the commutator cylinder, it is obvious that irregularly spaced bars connected to points in the armature symmetrically disposed electrically may be connected together 80 in the same manner to accomplish the same purpose.

From the foregoing description of what is shown in the drawing, it will be readily apparent that the cross connectors are readily accessible for repair and are provided with a firm and rigid support.

While I have shown and described my invention in its preferred form, it will be obvious to those skilled in the art that it is not so limited but is susceptible of various minor changes and modifications without departing from the spirit thereof, and I desire, therefore, that only such limitations

shall be placed thereupon as are imposed by the prior art or are set forth in the appended claims.

I claim as my invention:

5. 1. In a dynamo-electric machine, conducting bars and alternately disposed non-conducting bars constituting a hollow commutator cylinder, and a supporting sleeve located within said cylinder, a plurality of 10 said conducting bars being uniformly spaced and projecting from one end of said cylinder, and conductors mounted on said supporting sleeve and connecting the ends of equi-potential projecting bars, said conducting bars and said conductors being disposed at the same distance from the center.
15. 2. In a dynamo-electric machine, conducting bars and alternately disposed non-conducting bars constituting a hollow commutator cylinder, a supporting sleeve located within said cylinder, a plurality of said conducting bars being uniformly spaced and projecting from one end of said cylinder, spacing blocks of insulating material located between said projecting bar ends and conductors connecting projecting bar ends of equal potential, said conductors and said spacing blocks being mounted on, but insulated from, said supporting sleeve, and 20 banding material surrounding said projecting ends and said end-connecting conductors.
25. 3. In a dynamo-electric machine, conducting bars and alternately disposed non-conducting bars constituting a hollow commutator cylinder, a sleeve provided with a flange at its outer end disposed within said cylinder, a plurality of said conductor bars being uniformly spaced and projecting from 30 one end of said cylinder, insulating blocks disposed between said projecting portions, and conductors disposed adjacent the ends of said bars and connecting certain of them, the projecting portions of said conductors and the said connectors being supported upon said sleeve and supported between said blocks and the flange on said sleeve, and a continuous layer of insulation material disposed intermediate said projecting bars and said sleeve, said connectors and said flange, and on the outer periphery of the cylinder formed by said connectors and said projecting bars.
35. 4. In a dynamo-electric machine, a commutator cylinder comprising a plurality of alternately disposed conducting and insulating segments and a V-ring disposed within said cylinder, a plurality of said conducting segments being uniformly spaced and projecting from one end of said cylinder, conductors mounted adjacent said projecting ends and connecting together certain of them, said conducting segments and said conductors being disposed at the same distance from the center, and a sleeve integral with said V-ring disposed within said projecting segment ends and said conductors and supporting the same.
40. 5. In a dynamo-electric machine, a commutator cylinder comprising a plurality of alternately disposed conducting and insulating segments and a V-ring disposed within said cylinder, a plurality of said conducting segments being uniformly spaced and projecting from one end of said cylinder, insulating blocks disposed between said projecting portions, and conductors disposed adjacent the ends of said bars and connecting certain of them, the projecting portions of said conductors and the said connectors being supported upon but insulated from said sleeve and supported between said insulating blocks and the flange on said sleeve.

In testimony whereof, I have hereunto subscribed my name this 29th day of Dec. 1917.

CHARLES W. STARKER.
